METAL SURROUND

Guy L. Rosebrook, Oakland, Calif., assignor to E. R. Giffin, doing business as Giffin Aluminum Products Co.

Application July 6, 1953, Serial No. 366,173

4 Claims. (Cl. 189—75)

This invention relates to a metal surround for windows and the like and which surround includes the sill.

In windows, and particularly metal casement windows, it is customary to use a surround or frame comprising a headpiece, the jambpiece and sill pins, each having a channel portion extending longitudinally thereof and directed outwardly, into which is fitted and secured a web of the sash. This surround is intended to fit over the header, rough sill and jambs, trimmers or studs defining the window opening. The sash including the surround thereon can quickly be installed, since the headpiece, jambpieces and sillpiece of the surround each include a plate integral with the channel portion that is adapted to be nailed to the header, trimmers and rough sill, after which stucco or rustic may be applied to cover the plate that is secured to each of the above mentioned rough members that define the window opening.

Heretofore, such surrounds have either positioned the channel portion of the surround elements so they will interfere with the header, trimmers or rough sill or else the channel portion will interfere with the rustic trim that is later applied to the outside of the wall around the window. Such conventional structure requires chamfering one or more of the rough members defining its window opening or chamfering the rustic.

The principal object of the present invention is the provision of a surround that has all of the necessary and advantageous features necessary for securement to the sash of a metal casement window and which surround has a flat coplanar surface adapted to fit against the header, trimmers, and sill of the window opening without requiring any modification thereof, and which also is formed so that no modification of rustic is required when the latter is positioned around such opening and over a portion of the surround. In other words, by the present invention, it is not necessary for the workman to alter the header, trimmers and rough sill that define the window opening nor alter the exterior wall covering that extends over portions of the surround.

Other objects and advantages will appear in the description and in the drawings.

In the drawings,

Fig. 1 is a greatly reduced elevational view of a surround.

Fig. 2 is an enlarged sectional view taken along line 2—2 of Fig. 1 and which view shows part of the headpiece, header, rustic and part of the sash of a casement window.

Fig. 3 is an enlarged sectional view taken along line 3—3 of Fig. 1 showing a trimmer of the window opening, the jambpiece of this invention, and part of the casement sash.

Fig. 4 is an enlarged sectional view taken along line 4—4 of Fig. 1 showing the sillpiece, the rough sill of the window opening, rustic trim, and part of the casement sash.

In detail, the headpiece of the present invention is generally designated 1, the jambpieces 2, and the sillpiece 3. These are joined at their ends in any suitable

2

manner to provide a rectangular frame in which the headpiece and sillpiece are in horizontally extending parallel, vertically spaced relationship and the jambpieces are vertical and connect the corresponding ends of the headpiece and sillpiece.

Referring to Figs. 2, 3, 4, the window opening is usually formed by rough 2 inch by 4 inch pieces, the header being designated 4, the trimmers 5 and the rough sill 6. A stool 7 is normally positioned over the rough sill as indicated in Fig. 4.

The metal sash of the casement window has a coplanar flange that is continuous around the sash and therefore the surround is formed to provide a continuous inwardly directed or inwardly opening channel to receive the flange of the casement window.

In the headpiece 1 of Fig. 2, this channel portion is indicated generally at 10, and it connects with the portion 11 of each jambpiece (Fig. 3) and the ends of channel portions 11 of the jambpieces connect with the ends of the channel portion 12 of the sillpiece.

In Fig. 1 the flange 13 of the casement sash is shown extending into channel portion 10. In Fig. 2, the flange 14 of the casement sash is shown extending into channel portion 11 and in Fig. 3 the flange 15 of the casement sash is shown extending into the channel portion 12.

For purpose of identification, the sidewall of each channel portion that is at the room side of the surround will be called the "inner" side and the outer side wall of each channel portion will be the "outer" side. Inasmuch as the surround is outside the header, trimmers and rough sill, the inner sides of each channel portion will be the sides that are nearest such header, trimmers and rough sill.

The headpiece 1 of the surround has a vertically disposed face plate 17 that extends horizontally from end to end of the headpiece, and this plate 17 is coplanar with the inner side 18 of the channel portion 10. Thus the face plate and the inner side of the channel portion are adapted to be positioned flat against the header 4.

The jambpieces 2 are each provided with a vertically disposed face plate 19 that is coplanar with the inner side 20 of the channel portion 11, therefore the face plate 19 and inner side 19 of the jambpieces can be positioned flat against the trimmers 5.

The sillpiece is provided with a vertically disposed face plate 21 that is coplanar with the inner side 22 of the channel portion 12, therefore said face plate and inner side can be positioned flat against the rough sill 6 and stool 7 in such instances where the stool and rough sill are flush along their edges.

From the foregoing it will be seen that the inner face of the surround comprising the inner surfaces of face plates 17, 19, 21 and the inner surfaces of the inner sides 18, 20, 22 of the channel portions 10, 11, 12 are coplanar and are adapted to lie flat against the members defining the window opening without requiring alteration of said members.

The word "outward" or "outwardly" as used herein refers to direction relative to the wall of the building that is adapted to carry the surround, the outer side being the side opposite the room side.

Joining the face plate 17 of the headpiece at almost right angles thereto is an angularly outwardly extending head flange 25, and the portion of this flange along its juncture with the face plate defines the bottom 26 of the channel portion 10, said bottom being the portion of flange 25 that is along the juncture of the flange with the face plate.

The jambpieces 2 have substantially the same structure as the headpiece, there being a flange 27 joining face plate 19. The bottom 28 of the channel portion 11 is the portion of flange 27 that adjoins the face plate.

The sillpiece 3 is substantially the same structure as the headpiece in that flange 29 extends angularly from

the face plate 19, and bottom wall 30 of the channel portion 12 is the portion of the flange that adjoins the face plate.

Flanges 25, 27, 29 respectively have relatively narrow outwardly projecting flanges 31, 32, 33 along their edges that are remote from the channel portions 10, 11, 12 and the flanges 25, 29 are usually wider than flanges 27. Also flange 25 of the headpiece inclines downwardly slightly from the point where it joins the bottom 26 of the channel portion 10, and flange 29 also inclines slightly downwardly from the point where it joins the bottom 30 of the portion 12.

Sides 34, 35, 36 of channel portions 10, 11, 12 are respectively opposite sides 18, 20 and 21 and said sides 34, 35, 36 are respectively along the flanges 25, 27, 29 between the face plates 17, 19, 21 and the narrow flanges 31, 32, 33 are between said face plates and the outer edges of flanges 25, 27 and 29.

By the foregoing structure, rustic siding 40 or other outside wall structure can be placed directly over the outer sides of the face plates, and in abutting relation to the flanges 25, 27, 29 without modifying the rustic siding or walls in the slightest degree. Obviously, in stucco faced walls the stucco would replace the rustic. The fact that there is no obstruction along the outer sides of the face plates and flanges 25, 27 and 29 to the rustic siding or other panel or wall structure freely entering the corner defined by said face plates and flanges that enables the siding to be fitted around the surround without modifying the siding, and the fact that the face plates and sides 18, 20, 21 are coplanar enables the face plates to fit flat against the headers, trimmers and rough sill of the window opening without altering them.

As already mentioned, heretofore it has been necessary to chamfer the siding or the pieces forming the window opening in order to properly fit rustic siding to the surround or in order to properly position the surround around the window opening. With the present structure this difficulty is eliminated.

Reducing the structure of the headpiece, jambpieces and sillpiece to a general broad description common to all, it is seen that each part of the surround comprises an angle strip, one leg of which provides a face plate and the other leg of which provides a flange extending at an angle thereto, and an outwardly opening channel portion for receiving part of the window is provided along the flange at its juncture with the face plate with the bottom of said channel portion being part of the flange and in continuation thereof and with one side of said channel portion being a continuation of said face plate past the juncture between the flange and face plate, and with the other side projecting from said flange at a point between said one side and the free outer edge of the flange.

I claim:

1. A metal angle strip for part of a surround for a window providing a pair of legs extending at an angle to each other, one leg of said pair being a planar face plate adapted to fit flat against the outer side of a frame defining a window opening, said face plate having a substantial, unobstructed outer side for securing to said frame, the other leg of said pair being a flange for abutment with a wall covering along the reentrant side of the angle strip, a channel portion integral with said angle strip for receiving part of a window to be enclosed by the surround, said channel portion having a pair of opposed sides one of which is in coplanar continuation of said face plate past the juncture between the latter and said flange and the other side of said channel portion projecting from said flange along a line spaced between said one side and the free outer edge of said flange, a distance from said one side substantially less than the distance from said free outer edge, with the bottom of said channel portion being part of said flange along its juncture with said face plate.

2. A rectangular metal surround comprising a headpiece, jambpieces and a sillpiece with said pieces each defining one side of said surround, each of said pieces comprising an angle strip providing a pair of legs, one leg of each pair thereof being a planar face plate and the face plates of said pieces being coplanar for fitting flat against the frame defining a window opening, and having sides opposite said frame substantially unobstructed for access by fastening means, the other leg of each pair thereof being a flange projecting from the same sides of said face plates, channel portions integral with said pieces extending longitudinally thereof and opening inwardly relative to the surround, one side of each channel portion of each piece being in continuation of the face plate of such piece past its juncture with the flange, and the other side of each channel portion being a projection from the flange of each piece at a point between the face plate thereof and the free edge of the flange with the bottom of such channel portion being the portion of the flange adjoining the face plate.

3. In combination with a frame defining a rough window opening including a horizontally-extending, parallel, vertically-spaced header and sill and vertically-extending trimmers connecting the corresponding ends of said header and sill, a rectangular metal surround comprising: a headpiece, jambpieces, and a sillpiece with said pieces each defining one side of said surround, each of said pieces comprising an angle strip providing a pair of legs, one leg of each pair thereof being a planar face plate, the face plates of said pieces being coplanar and secured flat against one side of said frame and having sides opposite said frame substantially unobstructed for access by securing means, the other leg of each pair thereof being a flange projecting from said face plates away from said frame, channel portions integral with said pieces extending longitudinally thereof and opening inwardly relative to the surround, one side of each channel portion of each piece being in continuation of the face plate of such piece past its juncture with the flange, and the other side of each channel portion being a projection from the flange of each piece at a point between the face plate thereof and the free edge of the flange with the bottom of such channel portion being the portion of the flange adjoining the face plate.

4. In combination with a frame defining a rough window opening including a horizontally-extending, parallel, vertically-spaced header and sill and vertically-extending trimmers connecting the corresponding ends of said header and sill, a rectangular metal surround comprising: a headpiece, jambpieces, and a sillpiece with said pieces each defining one side of said surround, each of said pieces comprising an angle strip providing a pair of legs, one leg of each pair thereof being a planar face plate, the face plates of said pieces being coplanar and secured flat against one side of said frame and having sides opposite said frame substantially unobstructed for access by securing means, the other leg of each pair thereof being a flange projecting from said face plates away from said frame, channel portions integral with said pieces extending longitudinally thereof and opening inwardly relative to the surround, one side of each channel portion of each piece being in continuation of the face plate of such piece past its juncture with the flange, and the other side of each channel portion being a projection from the flange of each piece at a point between the face plate thereof and the free edge of the flange with the bottom of such channel portion being the portion of the flange adjoining the face plate, said point being closer to said face plate than to said free edge.
